UNITED STATES PATENT OFFICE.

WILLIAM T. SMITH, OF PHILADELPHIA, PENNSYLVANIA.

DESIGN FOR A RUG.

SPECIFICATION forming part of Design No. 15,778, dated February 3, 1885.

Application filed December 4, 1884. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in the representation of a male deer, with a landscape view in the background, and the whole

surrounded by ornamental borders, as shown 15 in the photographic print.

I claim—

The design for a rug, the same consisting of the representation of a male deer, with a landscape showing water on the right and foliage 20 and trees on the left in the background, surrounded by ornamental borders, as shown in the photographic print accompanying this specification.

W. T. SMITH.
